UNITED STATES PATENT OFFICE.

GEORGE W. MALLORY, OF BLENHEIM, ONTARIO, CANADA.

WICK-ADJUSTING MECHANISM.

1,197,046.

Specification of Letters Patent.

Patented Sept. 5, 1916.

Application filed March 3, 1916. Serial No. 81,801.

To all whom it may concern:

Be it known that I, GEORGE W. MALLORY, a subject of the King of Great Britain and Ireland, residing at Blenheim, in the Province of Ontario and Dominion of Canada, have invented certain new and useful Improvements in Wick-Adjusting Mechanism, of which the following is a specification, reference being had therein to the accompanying drawings.

The invention relates to adjusting mechanism for the wicks of lamps, oil-stoves, etc., and it is the object of the invention to provide a simple and novel construction for adjustably limiting the points to which the wick may be raised and lowered in successive operations, while permitting freedom for movement within said limits.

To this end the invention comprises the construction as hereinafter set forth.

In the drawings: Figure 1 is a sectional plan view of a portion of a wick burner, showing my improved wick-adjusting mechanism applied thereto; Fig. 2 is a side elevation; Fig. 3 is an elevation at right angles to Fig. 2; and Fig. 4 is a longitudinal section through the wick-adjusting stem.

A is a portion of a burner for a lamp, oil-stove or other device employing a wick.

B is the stem of the usual wick-adjusting device (not shown), and C is the wheel or handle for adjusting said stem.

My improvement is applicable to any construction of wick-adjusting mechanism having the elements just described, and comprises a worm-gear D sleeved upon the stem B, a worm E in mesh with said gear and mounted upon a laterally-extending stem F and a bracket G in which the stem F is journaled. In addition to the elements just described there is mounted upon the stem F a toothed wheel H and an extension I of the bracket G is formed in a spring pawl for yieldably engaging said toothed wheel to hold the same from accidental adjustment.

The worm-wheel D has a limited freedom of rotation upon the stem B, which is provided by a lost motion coupling between the stem and wheel, which as shown consists of a pin J on the stem extending into the path of a pair of spaced pins K and K' on the wheel. The amount of lost motion is sufficient to permit of raising and lowering the wick from a point which will extinguish the flame to the point of maximum height of flame without smoking.

To apply my improvement to an ordinary wick-adjusting device the worm-wheel D is sleeved upon the stem and preferably held from endwise displacement by sleeves 60 L and L' on opposite sides thereof. The pin J is then engaged with the stem and serves the double function of coupling the wheel to the stem and holding the sleeve L' in position. A further advantage of this construction is that in applying the attachment to an old burner the original stem may be cut from its wheel C, as indicated at M, so as to permit of slipping on the worm-wheel D, and subsequently the sleeve J may 65 be soldered or otherwise secured to the outer portion of the stem and coupled to the inner portion by the pin J, as shown in Fig. 4.

The bracket G may be attached to the burner by soldering or other suitable means, 70 said bracket being bifurcated to embrace the worm-wheel and furnish bearings for the stem F on opposite sides of said worm. As shown the two furcations G and G' are 75 separately attached to the burner, but it is 80 obvious that they might be made integral portions of the same member.

In use to originally set the mechanism the wick is lighted and by careful adjustment is so positioned as to give the maximum 85 flame without smoking. When in this position, the stem F is adjusted by means of its thumb-wheel N so as to take up all lost motion between the stem B and worm in the direction of rotation for raising the 90 wick. This will not, however, interfere with the turning of the stem B to lower the wick, and to such an extent as to extinguish the flame. Thus whenever the burner is 95 relighted it may be turned up to the limit of adjustment without danger of raising the wick too high and causing smoking. As the wick becomes consumed it is necessary to change this adjustment, which is accomplished by a rotation of the thumb-wheel N permitted by the yielding engagement of the 100 spring pawl I with the notched or toothed wheel H. This will rotate the worm, permitting a slight advance of the wick to a higher position, and after the operator becomes accustomed to the adjustment it will be easy to determine the amount required. In practice I have found that adjustment is only required once or twice a week and that one notch of the toothed wheel is sufficient 105 for each adjustment. The device is therefore one which may be easily manipulated 110

and accurately adjusted without exercise of any special skill or intelligence.

What I claim as my invention is:—

1. A wick adjusting device, comprising a rotative stem for directly actuating the wick raising and lowering mechanism, a worm-wheel having a lost-motion coupling engagement with said stem, a transverse stem having a worm thereon in mesh with said worm-wheel, a bracket in which said transverse stem is journaled, having an extension forming a resilient pawl, and a notched or toothed wheel on the transverse stem yieldably engaged by said pawl.
- 10 2. A wick adjusting device, comprising a rotative stem for directly actuating the wick raising and lowering mechanism, a worm-wheel having a lost-motion coupling engagement with said stem, a transverse stem, a worm on said stem in engagement with said worm-wheel, a bifurcated bracket embracing said worm in which said transverse stem is journaled, a resilient yieldable pawl formed by an extension of one of the furcations of said bracket, and a notched or toothed wheel on said transverse stem with which said pawl is yieldably engaged.
- 15 3. A wick adjusting device, comprising a rotative stem for directly actuating the wick raising and lowering mechanism, a worm-wheel sleeved upon said stem and having a pair of spaced pins projecting laterally therefrom, a pin projecting radially from said stem between said spaced pins and in the path thereof, a worm in mesh with said worm-wheel, a transversely-extending shaft on which said worm is mounted, a bracket in which said transverse shaft is journaled, said bracket being bifurcated to embrace
- 20 40 said worm, an extension of one of the furcations of said bracket bent to extend substantially parallel to the axis of said transverse shaft and forming a resilient pawl, and a notched or toothed wheel on said shaft with which said pawl is engaged.
- 25 45 4. A wick adjusting device, comprising a rotative stem for directly actuating the wick

raising and lowering mechanism, said stem being formed in two sections, the outer section having a thumb-wheel attached thereto, a worm-wheel sleeved upon the inner section of said stem, a sleeve forming a coupling between the two sections of said stem and abutting against said worm-wheel, a pin for coupling said sleeve to said stem extending laterally adjacent to said worm-wheel, a pair of pins projecting laterally from said worm-wheel on opposite sides of said radial pin and in the path thereof, a transversely-extending stem, a worm mounted on said stem in mesh with said worm-wheel, a thumb-wheel for rotating said stem, a notched or toothed wheel mounted on said stem, a bracket in which said stem is journaled, and a resilient yieldable extension of said bracket forming a pawl for engaging said toothed wheel.

5. A wick adjusting device comprising a rotative stem for directly actuating the wick raising and lowering mechanism, said stem being formed in two sections, a sleeve on the inner portion of said stem forming a shoulder thereon, a worm-wheel sleeved upon said inner portion of the stem and abutting against said shoulder, a sleeve secured to the outer portion of said stem telescopically engaging the inner portion thereof and forming a coupling between the sections, said sleeve also abutting against said worm-wheel, a pin extending radially through said sleeve and stem to rotatively secure the same to each other, said pin extending radially outward adjacent to said worm-wheel, a pair of spaced pins projecting laterally from said worm-wheel upon opposite sides and in the path of said radial pin, a worm in mesh with said worm-wheel, a transversely-extending shaft on which said worm is mounted, and a bracket in which said transversely-extending shaft is journaled.

In testimony whereof I affix my signature.

GEORGE W. MALLORY.
